UNITED STATES PATENT OFFICE.

FREDERICK GEORGE CREED, OF CROYDON, ENGLAND, ASSIGNOR TO CREED AND COMPANY LIMITED, A COMPANY OF GREAT BRITAIN.

PICTURE TELEGRAPHY.

Application filed February 17, 1926, Serial No. 88,861, and in Great Britain February 24, 1925.

This invention relates to improvements in that method or reproducing at a distance, a picture, drawing or other representation (hereinafter referred to generically as a picture) corresponding substantially to an original or master picture, by the aid of telegraphy, which consists broadly in traversing the various parts of the original picture by exploring means and causing the varying 10 character of such parts of the picture in relation to the character of the medium carrying the picture, to control an electric circuit in such manner as to vary the flow of current therethrough in accordance with the varying 15 character of the different parts of the picture, and utilizing such variation of current flow to punch in a telegraphic tape, a series of holes according to a predetermined code, representative of the varying character of the picture, 20 the tape so punched being afterwards used to transmit corresponding electric signals to telegraphic receiving apparatus adapted to utilize such signals to bring about, either directly, or indirectly, by another tape punched 25 to correspond to the transmitting tape, the printing on a suitable moving medium, of a series of dots representing, as to size and position, a picture corresponding substantially to the original picture.

30 The present invention has for its object to enable the reproduction of pictures by the general method hereinbefore mentioned, to be carried out in a better and more certain manner than heretofore and by means that 35 shall be comparatively simple in construction and more certain and effective in operation and in which the use of electric relays, solenoids or electro-magnets for operating the tape punching apparatus is avoided, such operation being effected wholly mechanically.

40 For this purpose, the invention consists broadly in causing a pencil of rays of energy to explore successive portions of the picture, drawing or other representation to be reproduced, (hereinafter referred to for brevity as a picture) and, according to the varying degree of density, or to the different character of the picture, at different parts thereof in relation to the medium bearing the picture, to vary the resistance of an electric circuit and then utilizing the resultant variation in current strength to move through the aid of electro-magnetic means, an arm or equivalent device to corresponding varying positions and

utilizing the varying positions of the said 55 arm or equivalent device to control mechanically, the operation of tape perforating apparatus and produce in a tape or equivalent, perforations according to a predetermined code, depending upon a selected number of 60 degrees in density or tones in the picture to suit the degrees of perfection required in the reproduction of the picture. The tape thus perforated is then utilized to telegraph by land or cable lines, or by wireless means, in 65 any known or suitable way, electric impulses or signals, according to the perforation in the tape, to telegraphic receiving apparatus adapted to utilize such impulses or signals, to operate or to control printing apparatus 70 comprising printing pins or points adapted to reproduce on a sheet of paper, a prepared wood block or other medium, moved, it may be, in a similar manner to the picture, a series of dots representing, as to size or density 75 and position, a picture corresponding with the original picture. Or the said electric impulses or signals can be used to operate telegraph receiving apparatus adapted to perforate a second tape in accordance with the 80 first one, the second perforated tape being afterwards utilized to operate or control printing apparatus of the kind mentioned, or to re-transmit corresponding electric impulses or signals to receiving and printing apparatus at another station.

85 The rays of energy used may be light rays or heat rays and act respectively upon a light sensitive medium, for instance a selenium cell, or upon a heat sensitive medium such as 90 metal or alloy having a high temperature coefficient of resistance, for instance a bolometer, associated in each case with an electric circuit provided with means for setting up an electric current therein so that according 95 to the varying or different action of the rays upon such sensitive medium, a variable or intermittent current will flow therein due to the varying nature of the picture.

100 As will be obvious, the invention can be carried into practice in various ways. It is specially adapted for the reproduction of photographic negatives or positives and the like mounted on a transparent base or carrier. The gradations of current in the electric circuit referred to will vary with the varying degrees of density of the picture. The number of different code signals em-

ployed to represent different values of the electric current will depend upon the degree of detail or perfection required in the reproduced picture. Thus, in such a reproduced 5 picture there may be one, two, three, four, or more series of dots of different sizes, each corresponding to a different signal. Assuming for instance that the reproduced picture is to be built up of dots of six different sizes, then 10 the total variation in the strength of the current set up in the electric circuit when the apparatus is in use, will in effect be divided into six degrees or stages by mechanical means, the strongest current corresponding 15 to the lighter parts of the picture to be reproduced by the smallest dots and the smallest current corresponding to the darkest parts of the picture to be reproduced by the largest dots.

20 The pencil of light or heat rays may be stationary and be produced by the aid of a lamp and a suitable condensing arrangement, the picture being arranged to move behind a screen having an aperture therein through 25 which the pencil of rays pass, and the light or heat sensitive medium or device be arranged behind the picture, opposite the aperture, and be included in an electric circuit. The picture, say in the form of a positive or 30 negative photographic film on a celluloid or other transparent base, may be in the form of a cylinder, or be applied to a transparent cylinder, that is intermittently or uniformly rotated and gradually moved endways so 35 that the pencil of rays will follow a helical path on the picture and ultimately traverse all portions of the latter. Or the picture may be moved endways and slightly sideways alternately, in an intermittent or uniform 40 manner, so that the pencil of rays will travel along a zig-zag course over the picture. In each case, the rays will pass in varying degrees through the different parts of the picture and impinge to varying degrees on the 45 sensitive medium so as correspondingly to affect the strength of current in the electric circuit referred to and in an electro-magnetic device associated therewith. The electro- 50 magnetic device may conveniently be in the form of an "ammeter" the pointer or arm of which will take up a position corresponding to the strength, for the time being, of the current in the electric circuit referred to, and depending, at the moment, upon the density 55 of the portion of the picture being dealt with. As the variation of current will usually be small and the movements of the pointer or arm correspondingly small, it will usually be desirable to utilize the movement of the said 60 arm to control apparatus adapted to produce amplified movements of another movable arm in accordance with the movements of the first mentioned arm. The extreme positions 65 of the movable arm may, in either case, be adjusted to the maximum and minimum de-

grees of light and shade in the picture to be reproduced. The intermediate positions or stages of movement of the arm may, in effect, be divided into any suitable number, say four, by using a number of broad spring controlled 70 feelers arranged circumferentially in relation to the path of the movable arm and so that they can move in a plane containing the axis about which the arm turns in order that when they are allowed to move, one or more 75 of them will be arrested by such arm in such manner that it or they will not tend to turn the arm one way or the other.

For punching perforations in a tape according to a code corresponding to the different spring controlled feelers selected by the arm moved under the control of the electro-magnetic device, the said feelers, which may be in the form of levers, may be placed under the control of releasing and returning 80 means that alternately releases them, so that they are free to move towards the arm, and afterwards return them to normal position, the said feelers being adapted to control tape punching mechanism in accordance with 85 their relative positions. Such mechanism may, for example, be similar in character to the tape punching mechanism described in the specification of Letters Patent No. 1,579,087, when adapted to punch tape according 90 to a three or other multiple unit system, the feelers referred to, taking the place of the key levers used in the said mechanism. In this case, during the working of the apparatus, the movable arm will take up varying positions corresponding to the varying strength 95 of the current for the time being in the electric circuit, and depending upon the varying densities of the picture being explored, the set of spring controlled feelers will be released 100 at regular intervals and the feeler or feelers that is or are at the moment of release opposite the arm, will be prevented thereby from moving or moving to its or their full extent, while the others will be left free and will 105 move to their full extent, with the result that the combination bars used in the punching apparatus will be relatively set to bring about the punching of perforations in a tape corresponding to the particular position of the 110 arm at the moment the feelers were released, the operation being repeated at regular intervals, corresponding to successive positions of the picture relative to the aperture through 115 which the pencil of energy rays pass. In this way, the number and position of the perforations punched in the tape as a result of each setting of the combination bars, will correspond to the particular position of the movable arm at the time when the feelers are released and consequently to the particular degree of density of the picture being dealt with 120 at the time.

The punched tape thus produced can afterwards be used as and when desired to trans- 125 130

mit in the ordinary way and it may be, by known transmitting means, as for instance a Wheatstone transmitter, electric signals or impulses, according to the predetermined 5 code, to telegraphic receiving and printing apparatus which may also be of known kind, adapted to print characters on a sheet of paper or the like, except that instead of printing letters or other characters, it must be 10 adapted to print dots of different sizes, according to the code and corresponding to the different degrees of density of the picture to be reproduced, as hereinafter more fully described.

15 In the accompanying illustrative drawings, Fig. 1 is a plan view, showing diagrammatically, one construction of apparatus adapted to perforate a tape, according to a predetermined code dependent upon a definite number 20 of varying degrees of density of a picture to be reproduced in accordance with the invention. Fig. 2 is a sectional elevation taken on the line II—II of Fig. 1. Figs. 3, 4 and 25 5 are detail views showing parts of the apparatus. Fig. 6 shows a piece of tape, perforated according to the invention. Fig. 7 shows in end view, a printing wheel used in telegraphic receiving and printing apparatus for reproducing a picture according to the 30 invention.

1 is a cylinder of glass or other transparent material upon which the picture 2 to be reproduced, consisting for example of a photographic positive or negative on a transparent 35 base or film, is mounted. The cylinder is fixed to a shaft 3 that is adapted to be slowly rotated in a continuous manner from an electric motor 4 through suitable driving mechanism, as for example a shaft 5, toothed 40 gearing 6, a second shaft 7, bevel gearing 8, third shaft 9 and worm gearing comprising a worm 10 on shaft 9 and a worm wheel 11. The latter wheel is connected to the shaft 3 by a key in the wheel fitting a key- 45 way in the shaft so that the latter will be rotated by the wheel 11 but can move endways therethrough. The diameter of the cylinder 1 and the value of the worm gearing 10—11 may be such that the cylinder 1, will, 50 for example, be turned through about one sixtieth of an inch on the circumference thereof for each rotation of the second shaft 7. The cylinder 1 is moved endways in a slow and continuous manner by forming a portion 55 of the shaft 3 to which it is fixed, with a fine screw thread 3^a, having say sixty threads to the inch, and arranging such screw threaded portion of the shaft to work through a stationary nut 12 so that it will move the 60 cylinder endways one sixtieth of an inch for each rotation thereof. 14 is a stationary opaque screen having a small aperture 15 through which a pencil of light rays 16 proceeding from any suitable light source 65 17 and condensed by suitable optical means 18, is caused to impinge upon the adjacent portion of the picture 2 on the cylinder 1, the amount of light energy passing through the picture at any time depending upon the density of the particular portion of the picture moving past the said aperture. 19 is a light sensitive device, for instance a selenium cell, arranged within the cylinder and directly behind the aperture 15 in the screen 70 14 so as to be affected in a variable manner according to the amount of light rays passing through the moving picture. The selenium cell arrangement 19 may be of known or suitable kind and include an electric circuit 20 comprising a battery 21, an adjustable resistance 22 and an electro-magnetic device 23. This device may advantageously be of the well known kind used with electric land or submarine cables for detecting small electric forces and which for this purpose 80 comprises a floating coil 24 arranged between the pole pieces N, S of a permanent magnet, and a stationary iron core arranged within the coil. 25 is an arm fixed to and moved by the coil to varying extents, according to 85 the strength of the current passing through it. It is this movable arm which is used to control the operation of tape punching mechanism in accordance with the invention. As the varying current in the circuit 20 will 90 usually be a small one, the movements of the arm 25 will also be small. It is therefore desirable to provide a second arm 25^a having a sufficiently large angular movement to enable the tape punching mechanism to be readily controlled thereby, and to provide between the main and supplementary arms 25 and 25^a 95 some suitable apparatus capable in effect of amplifying the small movements of the main arm 25 and producing a large movement of 100 the supplementary arm 25^a. For this purpose, in the example shown, there is arranged between the two arms 25 and 25^a apparatus of the kind described in the specification of 105 British Letters Patent No. 256,285, and 110 which, briefly described, comprises a number of fluid pressure receivers 26, 26^a and 26^b to each of which fluid under pressure is admitted at a suitable rate, and each of which is provided with an outlet nozzle 27, 27^a or 115 27^b, and pressure responsive means, such as a piston 28 (Fig. 4), subject to the variation in fluid pressure within the corresponding receiver and motion amplifying means such as a lever 29. The movable arm 25 is ar- 120 ranged to control the flow of fluid under pressure from the first receiver 26 and the pressure responsive device 28 in that receiver is arranged, by means of a baffling device 125 30^a carried thereby, to control the outlet of fluid under pressure through the nozzle 27^a, from the next receiver 26^a, the pressure responsive device in which is provided with a baffling device 30^b which controls the outlet of fluid under pressure through the nozzle 130

27^b of the third receiver 26^b, the pressure responsive device of which carries an abutment device 30^c adapted, through a rod or strut 31, to move the lever 29, which is pivoted at 29^a, in one direction against the action of a spring 32 which acts to move it in the opposite direction, according to the varying fluid pressure in the receivers, all as described in the specification of the said British Letters Patent No. 256,285. In this way the angular movement of the lever 29 will be considerably increased as compared with that of the movable arm 25 and will be operated by considerable force. The subsidiary arm 25^a for directly controlling the tape punching mechanism, is pivoted at 25^b and moved in one direction or the other through a link 33 from the motion amplifying lever 29.

The tape punching mechanism comprises a number of fingers, four in the example shown, in the form of levers 34, 34^a, 34^b, 34^c, each mounted to turn on a stationary spindle 35 and each provided on its lower side with a projection 34* for a purpose herein-after described. Each finger is connected to a spring 36 which normally holds it against one arm of a lever 37 pivoted at 37* and having a second arm 37^a. This latter arm is connected by a link 38 to one arm 39 of a lever pivoted at 40 and the other arm 39^a of which is provided with a roller 41. This roller is arranged to bear against the periphery of a came disc 42. This disc is fixed on a sleeve 7^a fixed on the rotary shaft 7. (hereinafter called the cam shaft). The periphery of the disc is formed with a recess 42^a into which the roller 41 will be forced by the action of a spring 43 connected to the lever 39, when the two come opposite each other during a part of each rotation of the cam shaft. By this means the lever 37-37^a will be turned about its pivot 37* and depress the arm 37 of such lever so as then to leave the fingers 34, 34^a, 34^b, 34^c free to fall. The said lever 37-37^a is moved into the position shown in Fig. 2, against the action of the said spring 43, by the concentric portion of the said cam 42 so as to cause the lever arm 37 to raise the said fingers to the normal position shown in Fig. 2. The movable arm 25^a is arranged to move under the free ends of the several fingers and above a stationary support 44. 45 are vertically movable T shaped locking members of sheet metal corresponding in number to the fingers 34-34^c and arranged to contact with suitably guided notched combination bars 46 of which there are three in the present example. The locking members 45 are raised to their inoperative positions above the combination bars 46 by one arm 47 of a two armed lever 47-47^a pivoted at 48. The said arm 47 is in the form of a plate that extends under all the T shaped members 45, and is connected to a spring 49 that tends to depress it. Each of the said locking members

45 is guided by a stationary guide 50 and is adapted to be moved downwardly by a spring 51 connected to one arm 52 of a lever pivoted at 53, and the other arm 52^a of which is jointed to the said member 45. To the pivoted end of each finger 34, 34^a, 34^b, 34^c is pivoted an upwardly extending stock arm 54 that is held against an upwardly extending arm 34^a of the corresponding finger 34-34^c by a spring 55 and is normally held opposite a notch 45^a in the corresponding locking member 45 so as to permit the said member being moved downward by its spring 51 when released by the downward movement of the arm 47 of the lever 47, 47^a. When the stop arm 54 is turned to the right, so that its upper end is brought under the portion 45^b of the locking member 45, the latter member is prevented from being moved downward by its spring 51 when released by the lever 47-47^a. This lever is moved quickly in one direction, about its pivot at 48, by a cam projection 56^a on a collar 56 on the cam sleeve 7^a engaging a roller 47^b on the lever arm 47^a once during each rotation of the said sleeve to raise the locking members 45 clear of the combination bars 46 against the action of the spring 49 which afterward moves the said lever 47-47^a into a position to release the said locking members and allow them to fall into engagement with the notched combination bars 46 if they be not held in their raised positions by the stop arms 54. The underside of the portion 45^b of each locking member 45 may be slightly recessed as shown to prevent the corresponding stop arm 54 when engaged therewith, being accidentally withdrawn therefrom by its spring 55, before the said locking member is positively raised by the lever 47-47^a.

The combination bars 46 are each provided (see Fig. 5) on its lower side with a projection 58 with which normally engages one arm 59 of a bar returning lever pivoted at 60 and the other arm 59^a of which is arranged to be operated by a cam groove 61 in the cam sleeve 7^a (Fig 1). Arranged in line with the respective combination bars 46 are punches 62 mounted to slide endways in a punch block 63 (Fig. 5) fixed in a frame 64 pivoted at 65 and jointed at 66 to one end of a link 67 the other end of which is jointed to one arm 68 of a lever pivoted at 69 and the other arm 68^a of which is arranged to be operated by another cam groove 70 in the cam sleeve 7^a. 71 is a die plate formed with perforations in alignment with the punches 62 and with a guide passage 72 for the tape to be perforated. 73 is a tape feed wheel fixed on a vertical spindle 74 and adapted to be rotated in an intermittent manner by a spring controlled pawl 76 which engages a ratchet wheel fixed on the said spindle 74 adjacent to the feed wheel 73. The pawl is pivoted to a lever arm 77 journalled on the spindle and oper-

ated by the rod 78 of an eccentric 79 fixed on the rotary shaft 9. The arrangement is such that the pawl 76 is caused to engage the ratchet wheel and rotate it and the feed wheel 73 sufficiently to feed the tape through a distance equal to three feed holes after each punching operation and to move backward independent of the ratchet wheel during each punching operation. 84 is a stationary pin 10 that prevents the punches 62 being moved to the left (Fig. 1) by the punch block 63.

The operation of the tape punching mechanism under the control of the movable arm 25^a, which is itself under the control of the 15 electro-magnetic device 23 and movable arm 25, as hereinbefore described, is as follows:—

Assuming that the various parts are at rest in the positions shown in Figs. 1 and 2, that fluid under pressure is being admitted to the 20 fluid pressure receivers 26, 26^a and 26^b and is issuing from the nozzles thereof at a predetermined rate and that the main and subsidiary arms 25 and 25^a are in the position shown, then, upon starting the motor 4 the 25 screw threaded shaft 3 and cam shaft 7 will be set in motion. The rotation and endways motion of the shaft 3 and of the attached cylinder 1 will cause each portion of the picture 2 to be brought between the aperture 30 15 in the screen 14 and the selenium cell 19 and across the path of the pencil 16 of light rays so that the latter will pass in varying degrees through the successive portions of the picture according to the density thereof.

35 The varying degrees of current thereby set up in the circuit 20 and electro-magnetic device 23 will cause varying angular movements of the main movable arm 25 and bring about variation in the rate of flow from the 40 fluid pressure receivers and cause a comparatively large angular movement to be imparted to the subsidiary movable arm 25^a. This arm can be adjusted so that its extreme positions will correspond with the extreme conditions of density in the picture 2 to be reproduced and with minimum and maximum current in the circuit 20. The cam sleeve 7^a is caused to make one revolution each time the cylinder 1 moves through one sixtieth of 45 an inch, measured in a rotary direction on its circumference, as assumed in the example taken. In the position of the parts of the mechanism shown in Fig. 2, the combination bars 46 are held in their forward or left hand 50 position (Fig. 1) by the returning lever 59—59^a with their forward ends adjacent to the rear ends of the punches 62 in the punch block 63 which has been moved into its forward position by the cam operating lever 60 56^a on the cam collar 56 on the cam sleeve 7^a has just acted to cause the lever 47, 47^a to raise the locking members 45 above the combination bars 46. The recess 42^a in the cam 65 42 then comes into position to permit the

roller 41 on the lever 39 to enter it under the action of the spring 43, and operate the lever 37—37^a in a direction to release all the fingers 34, 34^a, 34^b, 34^c and permit the same to be moved downward by their springs 36, except the one or adjacent two, that may be above the auxiliary movable arm 25^a. The downward movement of the fingers not arrested by the movable arm 25^a moves the corresponding stop bars 54 below the parts 45^b 70 of the corresponding locking members 45 and prevents the same descending under the action of their springs 51, whereas the finger or each finger arrested by the arm 25^a leaves its corresponding locking member 45 75 free to descend, under the action of its spring 51, and engage the corresponding combination bar or bars 46 so as to prevent backward movement thereof, that is to say, to the right in Fig. 1. The combination bars are thus 80 held to form a combination corresponding to the particular position at the moment, of the movable arm 25^a and therefore to the density of the particular portion of the picture then being dealt with. The arm 59 of the 85 return lever 59—59^a is then moved backward by the cam groove 61 so as to leave the combination bar or bars 46 not locked in position by locking members 45, free to move backward and the fingers are then returned to 90 normal by the lever 37—37^a so as to release the arm 25^a. The punch block 63 is then moved rearward by the cam groove 70, lever 68—68^a and link 67 to force the portion of the tape in the guideway 72 that is opposite 95 the punches, against such punches so that it will be perforated by the punch or punches 62 held stationary by the locked combination bar or bars 46, and will force the punch or punches opposite the unlocked combination 100 bar or bars idly backward without being punched thereby. The punch block 63 is then returned to its original position, the stationary pin 84 prevents the displaced punch or punches being moved beyond their proper 105 normal forward position, the tape feed mechanism is operated to move the tape forward sufficiently for the next punching operation, and the returning lever 59—59^a is operated 110 to return the displaced combination bar or bars to its or their normal forward position. The foregoing operations are then repeated 115 on the next revolution of the cam shaft 7 and sleeve 7^a. As hereinbefore stated, the cylinder 1 is arranged to be turned through say 120 about one sixtieth of an inch on the circumference thereof for each rotation of the shaft 7. Consequently sixty punching operations will be made under the control of the cam sleeve 7^a whilst one inch of the picture is 125 passing through the pencil of light rays 16, the diameter of which may also be equal to about one sixtieth of an inch in the example taken.

With the four fingers 34, 34^a, 34^b, and 34^c 130

and three combination bars 46, it is possible to punch, in the manner hereinbefore described, a tape A according to the code shown in Fig. 6, the perforations α corresponding to the six portions a, b, c, d, e and f of the tape, corresponding to the movable arm 25^b being below finger 34 or fingers 34—34^a, or below 34^a, or 34^a and 34^b, or below 34^b, or 34^b and 34^c, corresponding to the six degrees of density 10 in the picture to be dealt with. B are the ordinary feed holes in the tape A.

The punched tape thus produced can be used in known way, for transmitting electric impulses or signals to combined telegraphic 15 receiving and printing apparatus of any known or suitable kind. For this purpose, a Wheatstone transmitter may be used, which, owing to all the perforations α in the tape being on one side of the row of feed holes B 20 therein, will have one of the peckers, say the negative pecker, ordinarily used in such a transmitter, omitted. In this case a dot signal will be transmitted for every perforation α punched in the upper portion of the tape. 25 The receiving and printing apparatus used may conveniently be of the kind described in the specification of British Letters Patent No. 228,842, except that the printing wheel used in such apparatus, will only require a few 30 printing levers, namely six in the example now being described, each provided with a different sized pin or projection for printing dots, the different sizes of the dots so printed corresponding in area with the different densities 35 in the original picture. Fig. 7 shows a printing wheel 85 thus modified, 86 being the printing pins of different diameters carried by the printing levers 87 pivoted on the said wheel. Also, the sheet of paper or other medium 40 on which the pins are caused to print during the operation of the apparatus, should be arranged to be moved so that the reproduced picture represented by dots shall correspond faithfully with the original picture. 45 Thus, the printing of successive lines of dots of different sizes may be made on a web or sheet of paper carried by a cylinder that is moved longitudinally, in a step by step manner in a forward direction past the printing wheel (Fig. 7) until a line of dots of a 50 length corresponding to the circumferential length of the picture 2 on the cylinder 1 of Fig. 1 has been printed, the paper carrying cylinder being then, on the receipt of a special 55 signal for the purpose, caused rapidly to return to its initial starting position and be turned through a distance of one sixtieth of an inch and then again moved forward to print another line of dots, each line of dots 60 corresponding in length to one revolution of the picture carrying cylinder. The paper carrying cylinder and the mechanism for operating and controlling the same, may be similar to that described in the specification 65 of British Letters Patent No. 240,200. The

special signal for effecting the return and rotary feed motions of the paper carrying cylinder may be punched in the special code tape A (Fig. 6) at the end of each rotation of the picture carrying cylinder 1 (Fig. 1) 70 thus preventing any errors in transmission producing a cumulative effect when printing the lines of dots. For this purpose there may be arranged below the fingers 34, 34^a, 34^b, 34^c of the tape punching mechanism shown in Fig. 1 a stop bar 85 adapted, at the end of each revolution of the picture carrying cylinder 1, to be moved below the downward projections 34^x carried by the said fingers so as to prevent all the fingers falling when released by the 80 downward movement of the arm 37 of the lever 37—37^a. Consequently, when the locking bars 45 are released by the descent of the arm 47 of the lever 47—47^a, all of the said locking bars can be moved downward by their 85 springs 51 to lock all the combination bars 46 in position and enable the three punches 62 to punch a special set of perforations β in the tape A (Fig. 6) to form the special signal for bringing about the automatic return of the 90 printing cylinder and the rotary feed motion of the cylinder, hereinbefore referred to. The stop bar 85 may be operated by the armature 86 of an electro-magnet 87 the winding 95 of which is included in an electric circuit 88 that is adapted to be closed through two spring fingers or brushes 89 and 90 at the required times, namely at the end of each rotation of the cylinder 1, by an insulated contact 91 carried by an insulating disc 92 (Figs. 1 and 3) carried by and rotating with the worm wheel 11 (Fig. 1). The contact 91 should be of such length that contact with the fingers of brushes 89 and 90 will only be made during 100 one rotation of the cam sleeve 7^a. The punching of the special set of perforations β in the tape in the manner described, is caused to take place each time the joining line between the adjacent edges of the picture film wound round the cylinder 1 is passing the pencil of 105 light rays 16 so that the special signal produced by the special sets of perforations β in the tape and causing the rapid return and partial rotation of the paper cylinder used in the printing apparatus to its original position 110 for printing another line of dots, shall become effective each time a line of printed dots corresponding in length to the circumferential length of the picture cylinder 1, is 115 completed. 120 The electric impulses or signals transmitted by the punched tape instead of being used directly to operate receiving and printing apparatus, as desired, may be used to produce punched tape corresponding to the 125 original punched tape and which can be used to operate or control printing apparatus having a printing wheel and paper moving cylinder of the kind hereinbefore referred to. Examples of punching apparatus that may 130

be used for producing the secondary mentioned perforated tape, are described in the specification of British Patent No. 5,490 of 1905 and United States Patent No. 1,452,793, 5 and examples of printing apparatus adapted to be controlled by such perforated tape are described in the specifications of Letters Patents No. 1,534,164 and No. 1,529,873, the printing wheel of such apparatus being 10 modified as hereinbefore described and as shown in Fig. 7 to print dots of different sizes.

When reproducing black or opaque line drawings, diagrams, curves and the like, 15 drawn, printed or otherwise produced on a transparent base, a current will be set up in the aforesaid circuit 20 only when the light or heat rays pass through transparent portions of the drawing or the like and no current will flow through the circuit whilst a portion of the black or opaque line drawing intercepts the rays. In this case an intermittent current of constant strength with variable periods of no current will result. 25 The reproducing apparatus may in this case be modified, to suit, as the movable arms 25 and 25^a will have only two positions.

Various modifications may be adopted in carrying out the invention. For instance, 30 the light or heat rays instead of being passed through the different parts of the picture to be reproduced, may be reflected therefrom on to the light or heat sensitive device, for use in the manner hereinbefore described.

35 . What I claim is:—

1. For the production of punched tape for the purpose set forth, apparatus comprising a movable arm, electro-magnetic means adapted to move said arm to different positions corresponding to different degrees of density in the picture to be reproduced, mechanically operated punching mechanism adapted to produce on a tape perforations in accordance with a predetermined code, 40 depending upon a selected number of degrees of density in the picture to be reproduced, and mechanical means controlled by said movable arm and adapted to control said punching mechanism to effect selective operation thereof in accordance with the position 45 from time to time of said arm.

2. For the production of punched tape for use in the reproduction of pictures at a distance by telegraphy, apparatus comprising 50 an electric circuit, an electro-magnetic device controlled by current traversing said circuit, means for determining different degrees of density in the picture to be reproduced and thereby varying the strength of the current 55 in said circuit, an arm adapted to be moved by said electro-magnetic device to different degrees corresponding to different degrees of density in the picture to be reproduced, mechanically operated punching mechanism 60 adapted to produce in a tape, perforations 65

in accordance with a predetermined code, depending upon a selected number of degrees of density in the picture to be reproduced, said mechanism comprising a set of punches, combination bars adapted to hold said 70 punches stationary or leave them free to be moved endways, a punch block adapted to move endways in relation to a punch or punches held stationary by a combination bar or bars and having a guideway therein 75 for tape to be printed, and means for feeding tape intermittently through said guideway and mechanical means controlled by said movable arm and adapted to control said combination bars to effect selective 80 action thereof in accordance with the position from time to time of said arm.

3. In means for reproducing pictures at a distance by the aid of telegraphy, tape-perforating apparatus comprising an angularly 85 movable member, electro-magnetic means adapted to move such member to vary angular extents, a second angularly movable member, means adapted to cause the second named member to move synchronously with the first 90 named member but to an amplified extent, and punching mechanism adapted to be controlled by the said second member, substantially as described.

4. For the production of punched tape for 95 the purpose set forth, apparatus comprising a movable arm, electro-magnetic means adapted to move said arm to different positions corresponding to different degrees of density in the picture to be reproduced, me- 100 chanically operated punching mechanism adapted to produce in a tape, perforations in accordance with a predetermined code, depending upon a selected number of degrees of density in the picture to be reproduced, a second arm adapted to control said punching mechanism to effect selective operation thereof in accordance with the varying 105 position of said second arm and means whereby said second arm can be moved synchronously with the first mentioned arm but to an amplified extent.

5. For the production of punched tape for the purpose set forth, apparatus comprising a movable arm, electro-magnetic means 115 adapted to move said arm to different positions corresponding to different degrees of density in the picture to be reproduced, mechanically operated punching mechanism adapted to produce in a tape perforations in 120 accordance with a predetermined code, depending upon a selected number of degrees of density in the picture to be reproduced, a second arm adapted to control said punching mechanism to effect selective operation 125 thereof in accordance with the varying position of said second arm, and mechanical means whereby said second lever can be moved synchronously with the first men- 130 tioned arm but to an amplified extent.

6. For the production of punched tape for the purpose set forth, apparatus comprising means for supporting a picture to be reproduced, an electric circuit, a medium, sensitive to rays of energy included in said circuit, an electro-magnetic device having a winding also included in said circuit, means for producing a pencil of rays of energy, means whereby said support and a picture thereon can be moved relatively to the pencil of rays and across the path thereof so that said pencil of rays will explore successively all portions of said picture and affect the said medium sensitive thereto in varying degrees according to the varying density of successive portions of the picture and produce a corresponding varying current in said circuit, an arm adapted to be moved by said electro-magnetic device into different positions corresponding to the variations in flow of current in said circuit tape punching mechanism comprising a set of punches, combination bars adapted to hold said punches stationary or to leave them free to be moved endways, a motor operated punch block arranged to be moved endways in relation to a punch or punches held stationary by a combination bar or bars and having a guideway therein for tape, means for feeding tape intermittently through said guideway and means, under the control of said arm, adapted to hold one or more of said combination bars stationary and enable perforations to be produced in the tape, according to a predetermined code dependent upon and representative of varying degrees of density in the picture.

7. For the production of punched tape for the purpose set forth, apparatus comprising means for supporting a picture to be reproduced, an electric circuit, a medium, sensitive to rays of energy included in said circuit, an electro-magnetic device having a floating coil included in said circuit and mounted to oscillate in the field of said electro-magnetic device, means for producing a pencil of rays of energy, means whereby said support and a picture thereon can be moved relatively to the pencil of rays and across the path thereof so that said pencil of rays will explore successively all portions of said picture and affect the said medium sensitive thereto on varying degrees according to the varying density of successive portions of the picture and produce a corresponding varying current in said circuit, an arm adapted to be moved by said floating coil into different positions corresponding to the variations in flow of current in said circuit tape punching mechanism comprising a set of punches, combination bars adapted to hold said punches stationary or to leave them free to be moved endways, a motor operated punch block arranged to be moved endways in relation to a punch or punches held stationary by a com-

bination bar or bars and having a guideway therein for tape, means for feeding tape intermittently through said guideway, and means, under the control of said arm, adapted to hold one or more of said combination bars stationary and enable perforations to be produced in a tape, according to a predetermined code dependent upon and representative of varying degrees of density in the picture.

8. For the production of punched tape for the purpose set forth, apparatus comprising means for supporting a picture to be reproduced, an electric circuit, a medium, sensitive to rays of energy, included in said circuit, an electro-magnetic device having a floating coil also included in said circuit, means for producing a pencil of rays of energy, means whereby said support and a picture thereon can be moved relatively to the pencil of rays and across the path thereof so that said pencil of rays will explore successively all portions of said picture and affect the said medium sensitive thereto in varying degrees according to the varying density of successive portions of the picture and produce a corresponding varying current in said circuit, mechanically actuated tape punching mechanism and an arm adapted to be moved by said floating coil into different positions corresponding to the variations in flow of current in said circuit, a second movable arm adapted to control mechanically the punching action of said tape punching mechanism and enable perforations to be produced in a tape, according to a predetermined code dependent upon and representative of varying degrees of density in the picture, and a mechanical relay controlled by the first mentioned arm and adapted to move the secondly mentioned arm in synchronism therewith but to an amplified extent.

9. For the production of punched tape for the purpose set forth, apparatus comprising a cylinder for carrying the picture to be reproduced, mechanically operated tape punching mechanism, a motor driven shaft, cams on said shaft adapted to effect the setting and operation of the punching mechanism at each rotation of said shaft, mechanism adapted to rotate said cylinder from said shaft but at a slower speed than said shaft so that it makes only a small part of a revolution for each operation of the punching mechanism, an electric circuit, a medium sensitive to rays of energy, included in said circuit, an electro-magnetic device having its winding included in said circuit, means for testing the varying density of different parts of the picture on said cylinder and producing corresponding variations of current in said circuit, an arm movable by said winding to variable extents depending on the variations of current in said circuit, and mechanical means controlled by said arm, adapted to control said

punching mechanism to effect selective operation thereof in accordance with the position, from time to time, of said arm.

10. For the production of punched tape for the purpose set forth, mechanically actuated and controlled punching mechanism comprising a number of punches, combination bars adapted to hold said punches stationary or leave them free to be moved endways, a punch block adapted to move endways in relation to a punch or punches held stationary by a combination bar or bars and having a guideway therein for tape to be punched, and means for feeding tape intermittently through said guideway, an electric circuit, an electro-magnetic device having its winding in said circuit, means adapted to test the density of successive portions of the picture to be reproduced at a distance and produce variation in the strength of the current flowing in said circuit, dependent upon the varying degrees of density in the picture, an arm movable by said winding to varying positions dependent for the time being on the strength of current in said circuit, setting means for controlling the endways position of the combination bars in the tape punching mechanism, a series of levers adapted to move towards and from said movable arm and releasing and returning means adapted alternately to release the levers so that they are free to move towards said arm and afterwards to return said arms to normal position, said levers when so released, being adapted, under the control of said arm and according to their then relative positions to determine which punch or punches shall be brought into action to punch a hole or holes in the tape corresponding to the position, for the time being, of said arm.
40. 11. For the production of punched tape for the purpose set forth, apparatus comprising an electric circuit, an electro-magnetic device having a movable coil arranged in said circuit, an arm movable by said coil, means adapted to cause variation of current flow in said circuit and coil corresponding to different degrees of density of successive portion of a picture and thereby cause corresponding movements of said arm, mechanically actuated and controlled tape punching mechanism, a spring controlled second movable arm, means under the control of said second movable arm adapted according to varying position of said arm mechanically to control said punching mechanism so that such mechanism will be caused to punch in a tape, holes according to a code combination corresponding to the varying degrees of density of successive portions of a picture, and a mechanical relay adapted to cause the second arm to move synchronously with the first arm but to an amplified extent, said relay comprising fluid pressure receivers 60 each having an inlet and an outlet for fluid

under pressure, an endways movable piston therein and movable means for baffling the exit of fluid from each receiver, the baffling means for the first receiver being constituted by the first mentioned arm carried by said movable coil and the baffling means for each successive receiver being operated by the piston of the preceding receiver, and the piston of the last receiver being adapted to move said second arm against the action of its controlling spring, substantially as described.

12. In the production of punched tape for the purpose set forth, apparatus comprising an electric circuit, an electro-magnetic device arranged in said circuit, means adapted to cause variations of current flow in said circuit and electro-magnetic device corresponding to different degrees of density in successive portions of a picture, an arm adapted to take up different angular positions dependent upon the varying strength of current in said circuit and mechanically operated tape perforating mechanism controlled by said arm and comprising a set of tape perforating punches, a punch block, combination bars adapted to resist punch movement, motor mechanism adapted to move said punch block in relation to one or more punches held stationary by one or more combination bars, locking members normally disengaged from said combination bars, a series of pivotal fingers at least equal in number to the combination bars, stop arms pivoted to the fingers and normally adapted to offer no obstruction to movement of the locking members, a device for supporting the several fingers so that all the locking members occupy their initial position, and means for displacing the finger-supporting device said angularly movable arm being adapted to prevent displacement of all the fingers at a time, the fingers that are displaced permitting movement of the stop arms into position to obstruct the corresponding locking member.
13. For the production of punched tape for the purpose set forth, apparatus comprising an electric circuit, an electro-magnetic device arranged in said circuit and having a movable member, means adapted to cause variations of current flow in said circuit and electro-magnetic device corresponding to different degrees of density of successive portions of a picture and thereby cause corresponding movements of the movable member of said electro-magnetic device, an arm adapted to be moved to varying angular positions in accordance with varying movement of the movable member of said electro-magnetic device, a second angularly movable arm, means adapted to cause the second arm to move in synchronism with the first mentioned arm but to an amplified extent and mechanically operated tape perforating mechanism controlled by the secondly mentioned arm

and comprising a set of tape perforating punches, a punch block, combination bars adapted to resist punch movement, motor mechanism adapted to move said punch block
5 in relation to one or more punches held stationary by one or more combination bars, locking members normally disengaged from said combination bars, a series of pivotal fingers at least equal in number to the combination bars, stop arms pivoted to the fingers and normally adapted to offer no obstruction to

movement of the locking members, a device for supporting the several fingers so that all the locking members occupy their initial position, and means for displacing the finger supporting device, the said second angularly movable arm being adapted to prevent displacement of all the fingers at a time. 15

Signed at Paris, France, this fourth day of February, 1926.

FREDERICK GEORGE CREED.
